[57] ABSTRACT

The invention describes an electronic tone control circuit in which the tone can be influenced by means of a direct voltage. The tone control circuit includes two cross-connected differential amplifiers which each have a transistor connected in the emitter lead. The output signal is amplified by means of an operational amplifier. The input signal is applied via impedances to the bases of the transistors connected in the emitter leads which in turn are connected via impedances to the output of the operational amplifier. Depending upon the configuration of the impedance network the application of a direct voltage enables the higher frequencies and/or the lower frequencies to be boosted or attenuated.

CIRCUIT ARRANGEMENT FOR INFLUENCING FREQUENCY RESPONSE BY ELECTRONIC MEANS, IN PARTICULAR ELECTRONIC TONE CONTROL CIRCUIT

The invention relates to a circuit arrangement for influencing frequency response by electronic means, in particular to an electronic tone control circuit, which includes two amplifiers which have a common output and to the inputs of which is applied the signal the frequency response of which is to be influenced.

A circuit arrangement for correcting frequency response by electronic means is described in British Pat. specification No. 1,215,566. In this arrangement the signal is applied to a summing amplifier via three parallel channels which each include an amplifier provided with automatic gain control, the first channel passing the higher frequencies only, the second channel passing all the frequencies and the third channel passing the lower frequencies only. This circuit arrangement enables the transmission characteristic of the transmission medium, for example a telephone line, to be compensated.

In contradistinction thereto it is an object of the present invention to provide a circuit arrangement of the type referred to such as to enable the user to influence the frequency response in a simple manner by electronic means, i.e. by applying a control voltage, in particular a direct voltage. The circuit arrangement is in particular intended to be used as an electronic tone control circuit in, for example, the low-frequency section of a broadcast or television receiver.

According to the invention this is achieved in a circuit arrangement of the type referred to by a combination of the following features:

- a. The gains of the two amplifiers can be varied in opposite senses by means of a control voltage,
- b. the input signal is applied to the inputs of the two amplifiers via different impedance networks,
- c. the common output is connected to the inputs of the amplifiers by different negative-feedback impedance networks.

This circuit arrangement may largely be manufactured in integrated-circuit form if in an embodiment of the invention the two amplifiers include transistor differential-amplifier stages the collectors and bases of which are cross-connected, the control voltage being applied between the bases and the input signal being applied to each differential amplifier via an input transistor which is included in the emitter lead of the respective amplifier and the base of which serves as the input thereof.

Such a circuit arrangement provides a 180° phase shift but a comparatively low gain, because the emitter circuits of the input transistors must each include an emitter resistor for reasons of signal compatibility. Since in general a higher gain is required, in an embodiment of the invention the collector voltage of one half of the differential-amplifier transistors is applied to a high-gain amplifier — for example an operational amplifier — which does not produce a phase shift of the signal and the output of which serves as the common output.

In an embodiment of the invention the signal is applied via a first impedance to the input of one amplifier which via a second impedance is connected to the input of the other amplifier which in turn is connected via a

third impedance to the common output, the values of the impedances being selected so that the gain of the one amplifier changes in a sense opposite to that of the other amplifier with decreasing or increasing frequency.

As is known, the gain of a high-gain amplifier is equal to the ratio of the impedance between its output and its input to the impedance via which the input signal is applied to its input; hence the aforementioned selection of the values of the impedances must be such that the ratio of the sum of the second and third impedances to the first impedance has a frequency dependence opposite to that of the ratio of the third impedance to the sum of the first and second impedances.

In another embodiment of the invention the inputs of the amplifiers are each connected to the common input by an impedance and to the common output by another impedance, the values of the said impedances being chosen so that the gains of the two amplifiers vary in opposite senses with increasing or decreasing frequency. Such values are obtainable for example by a choice such that the impedance between the common input and the input of one amplifier is equal to the impedance between the common output and the input of the other amplifier.

In another embodiment of the invention, in order to simultaneously increase the gain or the attenuation of the high and low frequencies a resistor is included between the common input and the input of each amplifier, whilst a resistor is included between the common output and the input of one amplifier and an impedance network is included between the common output and the input of the other amplifier. If in a further embodiment of the invention the said impedance network is a band-pass filter which attenuates the high and low frequencies of a signal relative to the mid-band frequencies, and if this circuit is coupled to the volume control so that with decreasing volume the gain of the high and low frequencies is increased, a simple circuit is obtained for physiological volume control. If on the contrary the impedance network is a band-elimination filter having maximum attenuation in the range of the frequencies which determine speech intelligibility an electronically controllable overtone boost filter ("Prasenfilter") is obtained.

An embodiment of the invention will now be described, by way of example, with reference to the accompanying diagrammatic drawings, in which:

FIG. 1 is a schematic circuit diagram of a circuit arrangement for influencing the low frequencies according to the invention.

FIG. 2 is a graph showing the gain as a function of the frequency at various operating conditions.

FIGS. 3a and 3b show equivalent circuit diagrams illustrating the operation of the circuit arrangement of FIG. 1.

FIG. 4 shows an impedance network for influencing the high frequencies.

FIG. 5 shows an impedance network for influencing the low frequencies.

FIG. 6 shows an impedance network for influencing the high frequencies, and

FIG. 7 shows an impedance network which permits physiological volume control.

FIG. 1 shows a circuit arrangement according to the invention which may form part of an electronic tone control in an audio-frequency amplifier. The circuit ar-

arrangement includes two cross-connected differential amplifiers which each comprise two transistors and are so connected to one another that each of the four transistors T_1 to T_4 has one electrode in common with each of the three other transistors (for example the collector of the transistor T_1 is directly connected to the collector of the transistor T_2 , the emitter of the transistor T_1 is connected to the emitter of the transistor T_3 and the base of T_1 is connected to the base of T_4). A control direct voltage u_{KL} for electronic tone control is applied between the bases of the transistors T_1 and T_4 . The interconnected collectors of the transistors T_1 and T_2 are connected to a positive operating voltage via a resistor R whilst the interconnected collectors of the transistors T_3 and T_4 are connected to the positive operating voltage either directly or — for reasons of symmetry — via a resistor of the same value. The signal at the collector resistor R is applied to the input of an amplifier V which has a high gain and does not shift the phase of the signal. The output signal is taken from the output O of the amplifier V via a capacitor C_0 . The output O is also connected via a resistor R_2 of $10\text{ k}\Omega$ to the base E_2 of a transistor T_6 the collector of which is connected to the common emitter connection of the transistors T_2 and T_4 and the emitter of which is connected to earth through a resistor R_0 . The input E_2 is connected via a capacitor C of 39 nF shunted by a resistor R_3 of $150\text{ k}\Omega$ to the base E_1 of a transistor T_5 the collector of which is connected to the common emitter connection of the transistors T_1 and T_3 and the emitter of which is connected to earth via another resistor R_0 . The input E_1 is connected via a resistor R_1 of $10\text{ k}\Omega$ to a common input I to which the input signal u_{IN} is applied. The gain at low frequencies can be increased or reduced at will by varying the direct voltage u_{KL} between the bases of the differential-amplifier transistors.

The operation of the circuit arrangement will now be described with reference to FIGS. 2, 3a and 3b. Assuming that initially owing to the voltage u_{KL} the potential at the bases of the transistors T_2 and T_3 is negative relative to the potential at the bases of the transistors T_1 and T_4 , then the transistors T_2 and T_3 are cut off and the transistors T_1 and T_4 are conducting. The signal u_{IN} applied to the common input I is transmitted via the resistor R_1 , the transistors T_5 and T_1 and the differential amplifier V to the common output O . The series connection of the transistors T_5 , T_1 and the amplifier V may be replaced by an amplifier V' which has a high gain and shifts the phase of the input signal by 180° . (In this case the branch including T_2 and T_6 is cut off). Thus the equivalent circuit shown in FIG. 3a is obtained. A resistor R_3 of $150\text{ k}\Omega$ connected in parallel with a capacitor C is provided for adjusting the direct-current working points of the transistors T_5 and T_6 and furthermore determines the gain at low frequencies, as will be described hereinafter. At very low frequencies the impedance of the capacitor C is high relative to the resistor R_3 , so that the negative feedback from the common output O to the input E_1 of the equivalent amplifier V' is small; consequently the amplifier has a high gain V

$$V = \frac{R_2 + R_3}{R_1}$$

With increasing frequency the impedance of the capacitor C decreases and becomes small relative to the resistors R_2 and R_3 so that the negative feedback is increased and the gain is reduced. At frequencies exceeding about 250 Hz , which value is determined by the time constant of the capacitor C and of the resistor R_2 , the impedance of the capacitor C is negligible compared with the resistor R_2 . Hence the gain is largely determined by the ratio between the resistors R_2 and R_1 . Thus the gain of the circuit shown in FIG. 3a varies with the frequency according to the curve a of FIG. 2.

If however the voltage u_{KL} is such that the transistor T_2 is conducting and the transistor T_1 is cut off, the equivalent circuit shown in FIG. 3b is obtained. At low frequencies the impedance of the capacitor C is high so that the gain, which corresponds to the quotient of the impedance between the common output O and the input E_2 of the amplifier divided by the impedance between the input E_2 and the common input I , is very small. With increasing frequency the impedance of the capacitor C is reduced and the gain is increased. Above a limit frequency determined by the time constant R_1C the gain is determined only by the ratio R_2/R_1 . Thus when T_1 is cut off the gain varies according to the curve b shown in FIG. 2.

The frequency response between the curves a and b can be varied by variation of the voltage u_{KL} .

If in this circuit the resistors R_1 and R_2 are replaced by inductors and the capacitor C is replaced by a resistor, a suitable choice of the value of the inductors and of the resistor provides a circuit which also enables the gain between the curves a and b of FIG. 2 to be electronically influenced.

If, however, the resistors R_1 and R_2 are replaced by capacitors C_3 and C_4 respectively and the capacitor C is replaced by a resistor R_3 (FIG. 4), a circuit is obtained which enables the frequency response to be influenced above a limit frequency determined by the product R_3C_3 or R_3C_4 respectively so as to achieve the curves c and d of FIG. 2. The capacitors C_3 and C_4 may each have a capacitance of 6.8 nF and the resistor R_3 may have a resistance of $10\text{ k}\Omega$. To ensure the supply of direct current to the transistors T_5 and T_6 resistors of $100\text{ k}\Omega$ (shown in broken lines in FIG. 4) may be connected in parallel with the capacitors C_3 and C_4 , which resistors do not influence the alternating-current behaviour, because in this frequency range the impedance of the capacitors C_3 and C_4 is small compared with the respective shunting resistor.

When the output signal of a circuit arrangement as shown in FIG. 1 is applied to the input of a further similar circuit arrangement in which, however, the impedances R_1 , R_2 , and C are replaced by the impedances C_3 , C_4 and R_3 as shown in FIG. 4, an electronic tone control circuit is obtained which permits separate bass control and treble control by means of a direct voltage.

If the impedance network shown in FIG. 1 between the common input and output terminals I and O and the amplifier inputs E_1 and E_2 are replaced by the impedance network shown in FIG. 5, another circuit for influencing the low frequencies is obtained. In this arrangement the common input terminal I is connected to the input E_1 by the parallel combination of a capacitor C_1 and a resistor R whilst the output O is connected to this input E_1 by a capacitor C_2 . The common input I is connected to the amplifier input E_2 via a capacitor C'_2 whilst the common output O is connected to this

amplifier input by the parallel combination of a capacitor C'_1 and a resistor R' . Advantageously: $C_1 = C'_1$, $C_2 = C'_2$ and $R = R'$. Again the capacitors C_2 and C'_2 each are shunted by a resistor to ensure the supply of direct current to the transistors T_5 and T_6 . The limit frequency below which the frequency response of the gain can be influenced is determined by the time constant RC_1 in this arrangement.

If in this circuit arrangement each capacitor is replaced by a resistor and each resistor is replaced by a capacitor, an impedance network as shown in FIG. 6. is obtained which enables the higher frequencies to be influenced. The parallel combination of a capacitor C_5 of 1.8 nF and a resistor of $39 k\Omega$ is connected between the common input I and the input terminal E_1 . A resistor R'_6 of $39 k\Omega$ is connected between the input E_1 and the output O. The parallel combination of a capacitor C'_5 of 1.8 nF and a resistor R'_5 of $39 k\Omega$ is connected between the common output O and the input E_2 , whilst the input terminal I is connected to the input E_2 via a resistor R'_6 of $39 k\Omega$. Since this network passes direct current, separate shunting resistors for the supply of the direct current can be dispensed with.

If the impedance network of FIG. 1 between the terminals I, O, E_1 and E_2 is replaced by the impedance network shown in FIG. 7 in which a resistor R_8 is connected between E_1 and O, a resistor R_7 is connected between I and E_2 and a bandpass filter F which passes mid-frequency signals without attenuation and attenuates the higher and lower frequencies is connected between O and E_2 , a circuit arrangement for simultaneous boosting of the higher or lower frequencies is obtained.

If in this arrangement u_{KL} is chosen so that T_1 is conducting and T_2 is cut off, a frequency-independent gain of the value R_8/R_7 is obtained. If on the other hand T_2 is conducting and T_1 is cut off, a high gain is obtained for the high-frequency and low-frequency signals and a smaller gain for mid-frequency signals, because the mid-frequency signals pass through the bandpass filter F without attenuation and hence produce strong negative feedback.

When such an arrangement is combined with an (in particular electronic) volume control so that with reduced volume the transistor T_2 is highly conductive and the transistor T_1 is weakly conductive, the use of a bandpass filter having a suitable pass characteristic provides an acoustically correct (physiological) volume control.

If in the circuit arrangement shown in FIG. 7 the bandpass filter included between the output O and the input E_2 is replaced by a band-elimination filter which attenuates the signals at frequencies which are significant for speech intelligibility in a higher degree than the signals at the remaining frequencies, an overtone boost filter is obtained which in accordance with the polarity and value of u_{KL} is operative in a higher or lesser degree.

If in the circuit arrangement of FIG. 7 the resistor R_8 is replaced by a band-elimination filter (or R_7 by a bandpass filter), the higher and lower frequencies may be boosted and attenuated relative to the mid-frequencies.

What is claimed is:

1. A circuit arrangement comprising first and second amplifiers, each of said amplifiers having an input and an output; a common output terminal coupled to said amplifier outputs; first and second input impedance

networks having different transfer functions, each having an input means for receiving a single input signal and an output coupled to said amplifier inputs respectively; first and second feedback impedance networks for providing negative feedback around said amplifiers respectively, said networks comprising impedance means having different transfer functions, each having an input coupled to said common output terminal an an output coupled to said amplifier inputs respectively; and means coupled to said amplifiers for varying the gain of said amplifiers in opposite senses in accordance with a control signal.

2. Circuit arrangement as claimed in claim 1, wherein the two amplifiers each include a transistor differential-amplifier stage, the collectors and bases of said transistors being cross-coupled between a transistor of one stage to a transistor of another stage, like electrodes being coupled together, the control voltage being applied between said bases, two transistors which are each coupled to one of the emitter leads of said differential amplifier stage transistors and the bases of which comprises said inputs of the amplifiers respectively.

3. Circuit arrangement as claimed in claim 2, further comprising a high-gain amplifier which does not shift the phase of the signal having an input coupled to the collector of two of said differential amplifier transistors and an output which comprises the common output terminal.

4. Circuit arrangement as claimed in claim 1, wherein said first input network comprises a first impedance means for receiving the input signal and coupled to the input of said first amplifier, said second input network and said feedback means comprise a second impedance means coupled to the inputs of said first and second amplifiers, and a third impedance means coupled to the input of said second amplifier and to the common output terminal, the values of the impedance means providing that the gains of the two amplifiers depend upon the frequency of the input signal in opposite senses.

5. Circuit arrangement as claimed in claim 4, said second impedance means comprises a capacitor and said first and third impedance means each comprise a resistor, whereby the low frequencies are influenced.

6. Circuit arrangement as claimed in claim 4, said second impedance means comprises a resistor and the first and third impedance means each comprise a capacitor, whereby the high frequencies are influenced.

7. Circuit arrangement as claimed in claim 1, the values of the impedance means providing that the gains of the two amplifiers vary in opposite senses with increasing frequency and with decreasing frequency respectively.

8. Circuit arrangement as claimed in claim 7 further comprising means for influencing the lower frequencies, said networks including a first parallel combination of a first resistor and of a first capacitor coupled between the input means and the input of said first differential amplifier, a second capacitor coupled between said first amplifier input and said common output terminal, a third capacitor coupled between the input means and the input of said second differential amplifier, and a second parallel combination of a second resistor and a fourth capacitor coupled between said common output terminal and said other amplifier input.

9. Circuit arrangement as claimed in claim 7 further comprising means for influencing the higher frequen-

cies, said networks including a first parallel combination of a first capacitor and a first resistor coupled between the input means and the input of said first differential amplifier, a second resistor coupled between said first amplifier input and said common output terminal, a third resistor coupled between the input means and the input of said second differential amplifier, and a second parallel combination of a second capacitor and a fourth resistor coupled between said common output terminal and said second amplifier input.

10. Circuit arrangement as claimed in claim 1, further comprising means for controlling the higher and lower frequencies, said networks including three resistors, two coupled between the input means and each of the inputs of the two amplifiers respectively, the third coupled between the common output terminal and first amplifier input, and a band filter coupled between the common output terminal and the second amplifier input.

11. Circuit arrangement as claimed in claim 10, wherein said filter is a bandpass filter which attenuates the higher and lower frequencies of said input signal relative to the midfrequencies.

12. Circuit arrangement as claimed in claim 11, further comprising means for providing an acoustically and physiologically correct volume control, wherein the control voltage applied to the differential amplifier stages so depends upon the volume control that with decreasing volume the gain of the other amplifier is increased.

13. Circuit arrangement as claimed in claim 10 further comprising means for boosting the frequencies 10 which are significant for speech intelligibility, said filter is a band-elimination filter the maximum attenuation of which lies in the range of the frequencies significant for speech intelligibility.

14. Circuit arrangement as claimed in claim 1, further comprising means for controlling the higher and lower frequencies, said means comprising a bandpass filter coupled between the common output terminal and one amplifier input and a band-elimination filter 15 coupled between the common output terminal and the other amplifier input, and a resistor coupled between the two inputs and the input means.
